UNITED STATES PATENT OFFICE

BERNARD D. WILLIS, OF OAK PARK, ILLINOIS, ASSIGNOR TO AUTOMATIC ELECTRIC INC., OF CHICAGO, ILLINOIS, A CORPORATION OF DELAWARE

AUTOMATIC TELEPHONE SYSTEM

Application filed October 18, 1926, Serial No. 142,267. Renewed July 12, 1929.

This invention relates to automatic telephone systems in general, but is more particularly concerned with small automatic telephone exchange systems comprising relatively few lines; and the object of the invention, broadly stated, is the provision of new and improved automatic switching apparatus which is particularly suitable for use in such small automatic telephone systems, commonly known as community automatic exchange systems.

A particular feature of the invention is a new and improved connector switch which may be operated as an ordinary connector when extending connections to individual subscribers' lines, which may be operated as a code-ringing connector to signal a particular party on a party line either on the same line as the calling subscriber or on another party line, or which may be operated to extend a call over an outgoing trunk to some other telephone exchange, such as to the main automatic exchange of a neighboring city.

The object and features of this invention will be described in detail in the following specification with the aid of the accompanying drawings comprising Figs. 1 and 2, which, when Fig. 2 is placed to the right of Fig. 1, show by means of the usual schematic circuit diagrams the principal apparatus to be used in a community automatic telephone exchange.

In Fig. 1 of the drawings, the party line comprising conductors 2 and 3 serves the substations A and A' (and others not shown) and terminates at a community automatic exchange (abbreviated CAX) in the rotary lineswitch RLS. The substations are of the usual automatic type having ringers comprising two coils bridged across the line conductors in series with a three-plate condenser, the third plate of which is connected to ground. The individual lineswitch RLS is of the usual type, whose operation is well known and together with other rotary lineswitches has access to a ground of connectors, one of which is the connector C shown.

The connector C is of the well known Strowger vertical and rotary type of switch having a plurality of horizontal rows or levels

of contacts. The control circuits of the connector form a particular part of this invention, which will be explained in detail in the following specification. In the banks of the connector C access is had to subscribers' lines 55 in one or more levels, including the party line comprising conductors 102 and 103. The party line comprising conductors 102 and 103 terminates in the rotary lineswitch RLS' (not shown) which is similar to the rotary lineswitch RLS and serves substations A² and A³ (and others not shown) which are identical to substations A and A'. In a particular level in the banks of the connectors, access is had to outgoing trunks via repeaters, one of 60 which is shown comprising conductors 232 and 233.

The generator G supplies ringing current for signalling called subscribers. The busy machine B supplies busy tone current for giving 70 calling subscribers the busy tone when a busy line is connected with.

In Fig. 2, the repeater R individual to the trunk comprising conductors 232 and 233 is shown. The circuits of the repeater R are 75 slightly modified to operate in conjunction with the connectors of this new design, such as connector C, and will be described in detail hereinafter.

The trunk lines extending to the main exchange are two-way trunk lines and also terminate at the CAX in rotary lineswitches for extending calls from the main exchange to the CAX. The trunk line comprising conductors 232 and 233 terminates in the RLS² which is 85 similar to the rotary lineswitch RLS, and also has access in its banks to the connectors.

With this general description of the object of the invention and the apparatus used at the automatic exchange in mind, a detailed 90 description of the operation thereof will be given. For this purpose it will first be assumed that the subscriber at substation A desires connection with the subscriber at substation A³. To initiate the call, the subscriber at substation A removes his receiver and dials the number of the line to substation A³, and then dials the code for signalling the subscriber at substation A³.

Responsive to the removal of the receiver 100

the lineswitch RLS rotates its wipers 13, 14, and 15 to hunt an idle connector switch and extend the connection thereto. It may be assumed that the connector C is the one selected.

5 When the connector C is seized, a circuit is closed which may be traced from the bridge across the line conductors 2 and 3 at the calling station by way of armatures 8 and 10 and their working contacts (switching relay 5 operating when the connector C is seized), wipers 13 and 15, conductors 22 and 23, armatures 45 and 47 and their resting contacts, normally closed springs controlled by armatures 58 and 59, through the upper and lower 15 windings of line relay 33 to battery and ground. Line relay 33 operates and closes a circuit for the release relay 34. Release relay 34 operates and places ground potential on conductor 24 at armature 49, thereby marking 20 the connector C engaged, providing a holding circuit for switching relay 5, and also marking the calling line busy in the usual manner. At armature 50 a circuit is prepared for the lower winding of switching relay 41; 25 at armature 51 the impulsive path for operating the magnets of connector C is prepared.

Responsive to the dialing of the first digit, line relay 33 operates and sends a corresponding number of impulses to the vertical magnet 30 net 42. The path over which the first of these impulses is sent extends from ground by way of the resting contact and armature 46, armature 48 and the resting contact, armature 51 and the working contact, contacts 76, winding 35 of series relay 35, winding of vertical magnet 42 to battery; the remaining impulses traverse the same path except that the contacts 77 and armature 52 and the working contact are included, and contacts 76 are excluded, this by reason of the shifting of the off-normal springs upon the first vertical step 40 of the switch wipers. Relay 35 is energized in series with vertical magnet 42, and by reason of its slow-acting characteristic maintains 45 its armature 52 attracted throughout the sending of this series. The vertical magnet 42 operates responsive to the impulses sent thereto to raise the switch wipers 82, 83, and 84 opposite the level of bank contacts containing the desired line. At the termination 50 of this series of impulses, relay 35 deenergizes and by releasing its armature 52, extends the impulsive path to the rotary magnet 43 by way of armatures 62 and 72.

55 Responsive to the dialing of the next digit, line relay 33 again operates and sends a corresponding number of impulses to rotary magnet 43. Relay 40 energizes in parallel with rotary magnet 43, and due to its slow- 60 acting characteristic maintains its armatures attracted throughout the sending of impulses thereto. Responsive to these impulses, rotary magnet 43 rotates the switch wipers 82, 83, and 84 into engagement with the bank contacts 65 at which access is had to the desired

line, these in this case being bank contacts 92, 93, and 94, respectively.

If the line to substation A³ is busy at this time, ground potential will be present on bank contact 94. Then when wiper 84 is rotated into engagement therewith, a circuit is closed for the test relay 39, which includes armature 64 and the working contact, and armature 70 and the resting contact. Test relay 39 will then energize and connect the busy tone current supply to the lower talking conductor at armature 63 and prepare a locking circuit for itself at armature 61, which circuit is closed when relay 40 deenergizes and releases its armature 64 at the cessation of the impulses sent to the rotary magnet. The calling subscriber, hearing the busy tone, replaces his receiver, initiating the release of the operated switches as will be described later.

It will be assumed, however, that the line comprising conductors 102 and 103 is idle at this time. In this case, relay 39 does not operate and when relay 40 deenergizes and releases its armature 64 upon the cessation of impulses to the rotary magnet, a circuit is completed which may be traced from ground by way of the working contact and armature 50, armature 61 and the resting contact, through the lower winding of switching relay 41, closed shaft-springs 80, resting contact and armature 64, wiper 84, bank contact 94, private normal conductor 104, through the winding of the switching relay and winding of the stepping magnet of the rotary lineswitch RLS' (not shown) in series to battery. The current flow in this circuit is insufficient to cause the operation of the stepping magnet of the rotary lineswitch RLS', but the switching relay of the rotary lineswitch RLS' is operated to disconnect the normal ground and battery connections from the line conductors 102 and 103, and switching relay 41 is operated and performs the following circuit changes: At armature 68 a locking circuit is closed for the upper winding of relay 41. At armature 69 direct ground potential is placed on the test contact 94 and the other contacts multiplied thereto to mark the line engaged. A circuit is prepared for relay 39 at armature 70. A circuit is prepared for relay 37 at armature 71. Rotary magnet 43 is disconnected from the impulsive path at armature 72. A point is opened in the circuit of release magnet 44 at armature 73. A point in the busy tone circuit is opened at armature 75 and at armatures 67 and 74 normally open points in the talking circuit are closed.

The line to the desired substation has now been connected with and found idle, so the calling subscriber may now dial the digits to produce the code to signal the subscriber at substation A³. Responsive to the dialing of these digits, relay 40 operates, remaining

operated continuously during any one series, and during each operation functions to close a circuit for the ringing relay 37 at armature 65, this circuit extending from ground by 5 way of the working contact and armature 50, armature 61 and the resting contact, working contact and armature 71, working contact and armature 65, through the winding of relay 37 to battery. Relay 37 operates and 10 applies ringing current from the generator G over the two sides of the called line in parallel by way of working contact and armatures 55 and 56, condensers 55' and 56', armatures 58 and 59 and the resting contacts, 15 armatures 67 and 74 and the working contacts, wipers 82 and 83, bank contacts 92 and 93, line conductors 102 and 103, through the coils of the ringers of the substations on this line, through the three-plate condensers to 20 ground. The ringers of the substations on the line operate corresponding to the code produced, a long ring being produced by dialing the digit "8" and a short ring being produced by dialing the digit "2".

25 To answer the call, the subscriber at substation A⁸ removes his receiver, and in so doing places a direct current bridge across the line conductors 102 and 103 which closes a circuit for the battery feed relay 36, this 30 circuit including armatures 54 and 57 and their resting contacts. Relay 36 operates and closes a circuit for relay 39 at armature 53. Relay 39 now operates, closes a locking circuit for itself at armature 60, and disconnects 35 relay 40 from the impulsive path at armature 62, so that any further manipulation of the dial cannot cause the energization of ringing relay 37. The talking connection is now completed and the two subscribers may now 40 engage in conversation.

At the termination of the conversation, both subscribers will replace their receivers. When the subscriber at substation A replaces his receiver, the circuit of line relay 33 is 45 interrupted. Relay 33 then deenergizes and opens the circuit of release relay 34. Release relay 34 deenergizes and removes ground potential from release conductor 24, thereby opening the circuit of switching relay 5 of the rotary lineswitch RLS and also 50 interrupting the holding circuit of the switching relay 41. In releasing its armature 51, relay 34 also closes a point in the circuit of release magnet 44, off-normal springs 78 55 having closed upon the first vertical step of the switch wipers. Switching relay 41 deenergizes and restores its armatures to normal, and in so doing closes the circuit of release magnet 44 at armature 73 and 60 disconnects ground from the test contact 94 at armature 69, thereby marking the line to the substation A⁸ idle and also releasing the switching relay of the lineswitch RLS'. Release magnet 44 operates to restore the switch 65 wipers of the connector C to normal.

A subscriber on a party line may wish to converse with another party on the same line. To signal a subscriber on the same line as the calling subscriber, the calling subscriber removes his receiver and dials a special reverting call number, after which he dials the code digits of the subscriber with which he wishes to converse. To explain the operations performed, it will be assumed that the subscriber at substation A wishes to converse with 70 the subscriber at substation A'. The subscriber at substation A first removes his receiver and then dials the digits of the special reverting call number. Responsive to the removal of the receiver, the lineswitch RLS 75 is again operated to select and extend the connection to an idle connector, which will be assumed to be the connector C. Responsive to the dialing of the digits of the special reverting call number, connector C operates in 80 the manner described above to position the wipers 82, 83, and 84 on the contacts of the special number which are contacts 88, 89, and 90. Of this set of contacts, contacts 88 and 85 90 are dead, while contact 90 is connected to reverting call relay 38. After relay 40 releases its armature 64 at the cessation of the impulses of the second digit, this relay having operated in multiple with the rotary magnet, a circuit is closed which may be traced from 95 ground by way of the working contact and armature 50, armature 61 and the resting contact, through the lower winding of switching relay 41, shaft-springs 80, resting contact and armature 64, wiper 84, bank contact 90, 100 conductor 87, through the winding of reverting call relay 38 to battery. Relay 41 operates in this circuit, its useful operations at this time being the closing of the locking circuit 105 for its upper winding at armature 68, the opening of circuit for the rotary magnet 44 at armature 72, and the closing of the locking circuit for relay 38 at armature 69. Relay 38 operates and at armatures 58 and 59 prepares a circuit for signalling the desired subscriber over the two line conductors in parallel, and removes the short circuit from the 110 windings of impedance 32.

The subscriber at substation A now dials 115 the code digits to signal the desired subscriber. Responsive to the dialing of these digits, relays 40 and 37 operate as described previously. When relay 37 operates, a ringing circuit is closed from the generator G over the two sides of the line serving substations A and A' in parallel by way of working contacts and armatures 55 and 56, condensers 55' and 56', armatures 58 and 59 and their working contacts, resting contacts and armatures 45 and 47, conductors 22 and 23, wipers 13 and 15, working contacts and armatures 8 and 10, line conductors 2 and 3, through the two coils of the ringers of the substations on the line to ground. Removing 120 the short circuit from the windings of 125 130

the impedance 32 includes these windings in series with the windings of line relay 33. The windings of the impedance 32 are cumulatively wound as regards the parallel ringing circuit, so that the inclusion thereof in the bridge across the line conductors prevents all but a negligible amount of ringing current from passing to ground through the windings of the line relay 33.

10 The ringers of all the substations on the line respond to the ringing current according to the code dialed. The subscriber at substation A' answers the call by removing his receiver and commencing conversation.

15 Talking current is furnished through the windings of the impedance 32 and the windings of the line relay 33. The windings of impedance 32, as regards the series battery feed circuit, are differentially wound and thus 20 do not materially affect the line talking conditions.

25 At the termination of the conversation both subscribers replace their receivers which initiates the release of the automatic switches in the usual manner.

30 Any subscriber served by the CAX may also obtain connection with any subscriber in the distant main automatic exchange over a trunk accessible in the banks of the connectors. To 35 describe the operations performed in setting up such a connection, it will be assumed that the subscriber at substation A desires connection with some subscriber in the distant main automatic exchange. To establish this connection, the subscriber at substation A removes his receiver, dials one of the special numbers for outgoing service to the automatic exchange, and then dials the regular directory number of the desired subscriber.

40 Responsive to the removal of the receiver at the substation A, the lineswitch RLS again operates to select an idle connector switch and extend the connection thereto. Again it may be assumed that the connector C is the one selected. Responsive to the dialing of the first digit of the outgoing service number, connector C operates to raise its wipers opposite the level in which the trunks to the main automatic exchange are accessible. When 45 the wipers are raised to this level, the shaft springs are shifted, causing contacts 80 to separate and contacts 79 to close. Responsive to the dialing of the second digit of the outgoing service number, the connector C operates to rotate its wipers 82, 83, and 84 into engagement with the contacts terminating the 50 trunk to the distant main automatic exchange corresponding to the special number dialed, which in this case it will be assumed to be contacts 94', 95, and 96, respectively.

55 If the trunk line terminating in this set of bank contacts is busy at this time, direct ground potential will be present on the test contact 96 from which the test relay 39 will 60 operate in the usual manner to close a lock-

ing circuit for itself, and apply the busy tone to the calling line to inform the calling subscriber that this outgoing trunk to the main automatic exchange is busy at this time. The calling subscriber at substation A will thereupon replace his receiver, which initiates the release of connector C. If more than one trunk extending to the main automatic exchange is provided these other trunks will also be accessible in the same level as the first 75 trunk. A subscriber, finding the first busy, may successively dial the special numbers corresponding to these trunks which will be known to him until an idle one is connected with. If all the trunks to the main automatic exchange test busy, the calling subscriber must await such time when there is one idle before he can complete the connection.

80 It will be assumed in this case, however, that the trunk terminating in the bank contacts 94', 95, and 96 is idle at this time. In this system an idle trunk is marked by the connection of ground potential to the test contact through a high resistance, so that the current flow through the test relay at the 85 time of testing is insufficient to cause its operation. Thus, when wiper 84 comes in contact with test contact 96, a circuit is closed which may be traced from ground by way of resistance 219', armature 221 and the resting 90 contact, release conductor 204, bank contact 96, wiper 84, armature 64 and the working contact, resting contact and armature 70, through the winding of test relay 39 to battery. Due to the resistance 219', the current 95 flow in this circuit is insufficient to cause the operation of relay 39. Now when relay 40 releases its armature 54 shortly after the cessation of the impulses of the second digit dialed, a circuit is closed from ground by 100 way of resistance 219', to armature 64 as previously traced, resting contact of armature 64, contacts 79, through the winding of the switching-through relay 31, resting contact and armature 62, through the winding 105 of relay 40 and the winding of rotary magnet 43 in parallel to battery. Due to the combined resistance of resistance 219' and relay 31, the current flow in this circuit is insufficient to cause the operation of relay 40 or magnet 43. Switching-through relay 31 110 operates, however, and opens the circuit of relay 34 at armature 46, and at armatures 45 and 47 connects the conductors 22 and 23 directly to wipers 82 and 83, respectively, at 115 the same time disconnecting the line relay from in bridge of the the calling line conductors. Line relay 211 of the repeater R operates over the circuit including the bridge at the calling station and the two line conductors in series and closes a circuit for the release relay 212 at armature 215. A bridge across the outgoing conductors 232 and 233 is also prepared at armature 216. Relay 120 212 operates and places direct ground po-

tential on release conductor 204 at armature 217, prepares a circuit for the bridging relay 213 at armature 218, and closes a circuit for switching relay 214 at armature 219. In the 5 connector C, the release relay 34 releases its armatures and disconnects ground from release conductor 24 by the disengagement of armature 49 from its working contact, ground being immediately reapplied thereto, 10 however, by the engagement of armature 49 with its resting contact via contacts 79 and the resting contact and armature 64.

In the repeater R, relay 214 operates when its circuit is closed at armature 219 and 15 closes a circuit which may be traced from ground by way of the working contact and armature 223, through the winding of switching relay 251 of the rotary lineswitch RLS², through the winding of rotary magnet 259 to battery. The current flow in this circuit 20 is insufficient to cause the operation of the rotary magnet, but relay 251 operates and disconnects the normal battery and ground connections from conductors 232' and 233', 25 respectively. At armatures 222 and 224 the bridge across the outgoing conductors 232 and 233 is closed which causes the operation of the line relay in the incoming selector at the main automatic exchange in which the 30 outgoing trunk conductors terminate.

The subscriber at substation A now dials the digits of the regular directory number of the main automatic subscriber. Responsive to the dialing of each digit, line relay 211 deenergizes and reenergizes a corresponding number of times, opening the bridge across the outgoing trunk conductor 232 and 233 at armature 216 a corresponding number of times to operate the line relay of an automatic switch at the main automatic exchange 40 in the ordinary way. Furthermore, at each deenergization, a circuit is closed for relay 213 at armature 215, which relay operates to short circuit the impedance 225 and remove the short circuit from the resistance 226 45 at armature 220. By reason of the slow-acting characteristics of relay 213 and relay 212, these relays remain energized during the dialing of each digit. In this manner automatic switches in the main automatic exchange 50 are operated which complete the connection to the called subscriber.

After the connection has been completed and the called subscriber has removed his receiver to answer the call, conversation may 55 take place. At the termination of the conversation, both subscribers will replace their receivers. Replacing the receiver at substation A opens the circuit of line relay 211 in repeater R. Relay 211 deenergizes and at 60 armature 216 opens the bridge across the outgoing trunk conductors 232 and 233, thereby causing the release of the automatic switches in the main automatic exchange 65 in the usual manner. Relay 211 in

deenergizing opens the circuit of relay 212. Relay 212 deenergizes and removes ground potential from the release conductor 204, thereby opening the circuit of the switching-through relay 31 in the connector C. Relay 70 31 deenergizes and in releasing its armature 46 completes the circuit for the release magnet 44. Release magnet 44 operates to restore the wipers of the connector C to normal. The removal of ground potential from the release conductor 204 also removes ground potential from the release conductor 24, thereby again marking the line to substation A idle and causing the release of switching relay 5 of the rotary line switch RLS. 75

Release relay 212 of repeater R in deenergizing, also opens a point in the circuit of relay 213 at armature 218, and opens the circuit of switching relay 214 at armature 219. Relays 213 and 214 deenergize and restore their armatures to normal. The release of armature 223 opens the circuit of switching relay 251 of the rotary line switch RLS². Relay 251 then deenergizes and restores its armatures to normal. All the switches are 80 now at normal, and may be taken for use to complete another call.

As previously mentioned, the trunk lines extending from the CAX to the main automatic exchange are two-way, and therefore 85 connections may be established from the main automatic exchange to any subscriber in the CAX. To establish such a connection, a calling subscriber first dials a special number to reach the CAX after which he dials 90 the regular directory number of the desired subscriber at the CAX, which includes the two line selecting digits and the code selecting digits if the desired subscriber is on a party line. When a trunk, for example the one comprising conductors 232 and 233, is seized at the main automatic exchange for 95 extending such a connection, a bridge is placed across the trunk conductors which cause rotary lineswitch RLS² to rotate its 100 wipers in search for a trunk extending to an idle connector. When an idle connector is 105 found, switching relay 251 operates to extend the connection to the selected connector and places direct ground potential on the 110 test contact 96, and the test contacts multiply connected therewith, by way of release conductor 204 at armature 254, thereby marking this trunk engaged. The seized connector 115 now operates responsive to the remaining digits just as did connector C as described 120 previously.

A particular feature of the connector is that should it become desirable to dispense 125 with rotary lineswitches in the C.A.X. (in case the number of lines does not warrant their use), the connector C may be connected directly to a subscriber's line without the addition of any relays or change in the circuits. When this is done, the switching re- 130

lay 31 of connector C also functions as a cut-off relay to cut off the then normal ground and battery connections through the line relay 33 when the line to which connector C is directly connected is called.

5 This completes the description of the operation of the new and improved connector and the apparatus associated therewith. What is thought new and is desired to have 10 protected by Letters Patent will be specifically stated in the appended claims.

What is claimed is:

1. In a telephone system, a connector switch, a trunk line terminating in said switch, a calling line, means for connecting said calling line to said switch via said trunk line, a second line, impulsing contacts at a station on said calling line, and means responsive to the actuation of said contacts for then operating said switch either to connect with said second line and signal a subscriber thereon or to signal another subscriber on said calling line via said trunk line.

2. In a telephone system, a connector switch, a trunk line terminating in said switch, a plurality of subscribers' lines each accessible in a separate set of contacts in the banks of said switch, a special set of contacts in the banks of said switch, means controlled over any one of said lines for establishing a connection with said switch via said trunk line, and means controlled over the connected line for operating said switch either to any one of said separate sets of contacts to signal 35 a subscriber on the corresponding line accessible in that set, or to said special set of contacts to cause said switch to signal a subscriber on the connected line via said trunk line.

40 3. In a telephone system, a connector switch, a trunk line terminating in said switch, a calling line and a second line, means for connecting said calling line to said switch via said trunk line, and means controlled over the two sides of the calling line in series for then operating said switch either to connect 45 with said second line and signal a subscriber thereon over the two sides of said second line in parallel or to signal a subscriber on said calling line over the two sides of said calling line in parallel.

4. In a telephone system, a connector switch, a trunk line terminating in said switch, a calling line and a second line, 55 means for connecting said calling line to said switch via said trunk line, means for then operating said switch either to connect with said second line and signal a subscriber thereon or to signal a subscriber on said calling line, said last means including a line relay bridged across said trunk line, an impedance connected in series with said line relay having windings differentially wound with respect to the windings of said line relay 60 and normally short-circuited, and means for

removing said short circuit when a subscriber on said calling line is signalled.

5. In a telephone system, a subscriber's line, a connector switch connected to said line, trunk lines and other lines accessible to 70 said switch, means for operating said switch to connect with any one of said other lines or said trunk lines, means in said switch operable when a subscriber's line is connected with for applying signalling current to the called line, a single-wound relay in said switch operable when a trunk line is connected with for disabling said signalling means, a second switch having access to said first subscriber's line, means for operating said second switch to connect with said first subscriber's line, and means responsive to said connection for 75 operating said relay.

6. In a telephone system, a subscriber's line, a connector switch, trunk lines and other subscribers' lines accessible to said switch, means for operating said switch to connect with any one of said other subscribers' lines or any one of said trunk lines, said means including a line relay controlled over said first subscriber's line, means in said switch controlled by said line relay for signalling the called subscriber when a subscriber's line is connected with, a second relay in said switch, means for operating said second relay over the trunk line when a trunk line is connected with for disconnecting said line relay.

7. In a telephone system, a connector switch adapted either to be individual to a subscriber's line or to be accessible to a plurality of subscribers' lines, trunk lines and subscribers' lines accessible to said switch, means including a line relay controlled over a calling line for operating said switch to connect with one of said subscribers' lines or with one of said trunk lines, a second relay in said switch having a single winding, means for closing a circuit for said winding to operate said second relay when a trunk line is connected with for disconnecting said line relay, and means operable in case said connector switch is individual to a subscriber's line for closing a circuit for said winding to operate said second relay when a second connector switch is operated to connect with the subscriber's line to which said first connector switch is individual.

8. In a telephone system, an automatic switch, means for directly operating said switch, a first and a second switching relay in said switch, a test wiper for said switch normally connected to a terminal of said first relay, and means responsive to the operation of said switch to a certain extent for disconnecting said test wiper from said first relay and connecting it to a terminal of said second relay.

9. In a telephone system, an automatic switch a line relay bridged across the trunk line terminating in said switch and controlled

thereover for operating said switch, means in said switch for ringing back over said trunk line, an impedance coil, and means for connecting said coil in series with said line relay during the ringing period.

- 5 10. In a telephone system, a trunk line, means for transmitting a series of impulses over said trunk line in one direction and a relay bridged across said trunk line and responsive to said impulses to cause the transmission of ringing current over said trunk line in the other direction during the transmission of said series of impulses.

10 15. In a telephone system, a trunk line means for transmitting impulses over said trunk line in one direction a relay bridged across said trunk line and responsive to said impulses to cause the transmission of ringing current over said trunk line in the other direction, and means operated during the ringing period for preventing the ringing current from interfering with the operation of said relay.

20 25. In a telephone system, means including a connector switch for connecting a calling subscriber's line and a called subscriber's line, means for operating said switch over the two sides of the calling line in series, and means in said switch for signalling the called party over the two sides of the called line in parallel.

30 35. In a telephone system, a combined connector and ringback switch, a trunk line terminating in said switch, and means in said switch for operating the same either to signal a called line or to ring back on a calling line over the two conductors of said trunk line in parallel.

40 45. In a telephone system, a combined connector and ringback switch, said switch being accessible to calling lines and having wipers for connecting to called lines, means in said switch for signalling a called line over a circuit including said wipers, and means controlled by the calling device on a calling line for signalling the calling line over a circuit excluding said wipers.

50 55. In a telephone system, a combined connector and ringback switch, said switch being accessible to subscribers' lines and having wipers for connecting to subscribers' lines, and means in said switch for signalling a called subscriber either over a circuit including said wipers and the two sides of the called line in parallel when the called subscriber is on some line other than on the calling line or over a circuit excluding said wipers when the called subscriber is on the same line as the calling subscriber.

60 65. In a telephone system, an automatic switch and means for operating it, talking conductors extending through said switch and divided into two serially connected sections, a ringing relay in said switch, and means for operating said ringing relay under

certain conditions to project ringing current over the first section of said conductors to the exclusion of the second, and under certain other conditions to project ringing current over the second section to the exclusion of the first.

70 75. In a telephone system, an automatic switch, a trunk terminating in said switch, a called line, a calling device for controlling the operation of said switch to connect, under certain conditions, with said called line, means responsive to the operation of said calling device when said called line is connected with to signal over the called line, and responsive to the operation of said calling device under certain other conditions to signal back over said trunk.

80 85. In a telephone system, a trunk line, a line relay adapted to be intermittently operated responsive to a series of current impulses sent over said trunk line in one direction, and means responsive to the intermittent operation of said relay and effective throughout a series of impulses for signalling back over said trunk line in the other direction.

90 95. In a telephone system, a calling subscriber's line, a trunk, means for connecting said line to said trunk, and a signalling device terminating said trunk and controlled over the two conductors of said line in series for signalling back over the two conductors of said trunk in parallel.

100 105. In a telephone system, a calling line, and means controlled over the two conductors of said line in series for signalling back over the two conductors of said line in parallel contemporaneously with the exercise of said control.

110 115. In a telephone system, an exchange, a party line terminating at the exchange, and means at the exchange controlled over the two conductors of said line in series from one station on said line for signalling the subscriber at another station on said line over the two conductors of said line in parallel during the time that the control is being exercised.

120 125. In a telephone system, a party line, means for establishing a flow of current over the conductors of said line, means at one station on said line for intermittently interrupting said current flow, and means responsive to and effective during said intermittent interruptions for signalling another station on said line.

130 135. In a telephone system, a party line, means for establishing a flow of current over the conductors of said line, means at one station on said line for intermittently interrupting said current flow, and means for automatically applying a source of signalling current to said line while said initial flow of current is being intermittently interrupted to signal another station on said line.

24. In a telephone system, a combination connector and reverting call switch, normally operating as a connector, and a relay responsive to the operation of the switch to a particular position for converting it into a reverting call switch.
25. In a telephone system, a trunk having a release conductor, means for placing direct ground potential on said conductor when the trunk is busy and for placing ground potential through a resistance on said conductor when the trunk is idle, a switch and means for operating it to connect with said trunk, a busy test relay and a switching relay successively connected to said conductor when said connection is established, said busy test relay being responsive to the presence of direct ground potential on said release conductor to prevent the operation of said switching relay, and said switching relay being responsive to the presence of ground potential through said resistance to complete a talking connection over said trunk line.
26. In a telephone system, a connector switch having access to both subscribers' lines and trunk lines, means for operating said switch, a single set of wipers in said switch for connecting with the bank contacts of said subscribers' lines or said trunk lines, talking conductors in said switch, a switching relay in said switch for connecting the talking conductors to said wipers, a switching-through relay for connecting the talking conductors to said wipers, means for operating said first relay in case the wipers come to rest on the bank contacts of an idle subscriber's line, and means for operating said second relay in case the wipers come to rest on the bank contacts of an idle trunk line, said relays being operated independent of each other.
27. In a telephone system, a connector switch having access to both subscribers' lines and to trunk lines, means for operating said switch, a single set of wipers for connecting with the bank contacts of said trunk lines or said subscribers' lines, talking conductors in said switch, a switching relay in said switch for connecting the talking conductors to said wipers, a switching-through relay for connecting the talking conductors to said wipers, a circuit for said first relay, a normally open circuit for said second relay, means for closing said first circuit to cause the operation of said first relay to connect the talking conductors with said wipers in case the wipers come to rest on the bank contacts of an idle subscriber's line, means for operating said first circuit and for closing a point in said second circuit responsive to the operation of said wipers opposite a group of trunk lines, and means for closing a second circuit to cause the operation of said second relay to connect the talking conductors with said wipers in case the wipers come to rest on the bank contacts of an idle trunk line.
28. In a telephone system, a connector switch having access to subscribers' lines and to trunk lines through a single set of wipers, means for operating said switch, talking conductors in said switch, a relay operated only in case said wipers connect with an idle one of said subscriber's lines, a second relay operated only in case said wipers connect with an idle one of said trunk lines, and contacts on said relays for connecting said talking conductors to said wipers.
29. In a connector switch adapted to extend connections to subscriber's lines or to trunk lines through a single set of wipers, talking conductors, two switching relays for connecting said talking conductors to the wipers, and means for independently operating either relay depending on the type of line connected with.
30. In a switching device adapted to extend connections to two classes of lines through a single set of wipers, two switching relays for completing talking connections through the wipers, and means for operating one or the other of said relays depending on the class of line connected with.
31. In a telephone system, a trunk comprising two conductors, an impulsing circuit including the two conductors of said trunk in series, a signalling circuit including the two conductors of said trunk in parallel, means for simultaneously transmitting impulses over said first circuit and ringing current over said second circuit, and means for preventing interference between said circuits.
32. In a telephone system, a trunk line, a signal operative responsive to the application of alternating current to said trunk line, an automatic switch, a line relay bridged across the conductors of said trunk line and responsive to direct current impulses sent over said trunk line for controlling the operation of said automatic switch, and means for substantially preventing the passage of alternating current through said line relay when such current is applied to said trunk line to operate said signal.
- In witness whereof, I hereunto subscribe my name this 15th day of October, A. D. 1926.
- BERNARD D. WILLIS.
